UNITED STATES PATENT OFFICE

ANDERS HILMER OLSSON, OF LIDKOPING, SWEDEN

SMOKING PIPE

Application filed June 6, 1927, Serial No. 196,882, and in Sweden November 30, 1925.

The chief trouble with the ordinary smoking pipe is that liquid combustion products, as a result of the combustion proceeding from the top downward, are deposited within the 5 unburnt tobacco with the result that they finally, when the smoking has gone on long enough, accumulate on the bottom of the pipes and in the beginning of the smoke-conduits. This oil, known as pipe oil, which 10 every smoker is trying to avoid, is easily drawn into the mouth-piece of the pipes and thus prevents the enjoyment even of the very best tobacco.

For this reason numerous attempts have 15 been made to separate the pipe oil but in spite of these attempts most of the commercial pipes are suffering more or less from faults in this respect.

The present invention has for its object 20 to prevent the formation of pipe oil and is characterized principally by the fact that the construction of the pipe permits the combustion of the tobacco to proceed from below upwards. The liquid combustion products in 25 this way gravitate, as they are formed, down into the burning tobacco, where they are burnt without inconvenience to the smoker.

An embodiment of the invention is illustrated in the accompanying drawing. Fig. 30 1 is a longitudinal section and Figs. 2 and 3 show the pipe viewed from the end and the top. Fig. 4 is an elevation of the lid viewed from the direction of the mouth-piece of the pipe.

35 In the pipe bowl 1, there is inserted a combustion shell 2, the lower part of which is open and the upper part of which is provided with a spherical bottom. This bottom is perforated by a series of small apertures 40 3, thus connecting the interior of the combustion shell with the cavity 4 turned out in the pipe bowl. Extending from this room is the tube 5 which in turn is connected with a mouth-piece 6 of the ordinary type. In addition, the pipe bowl 1 is provided with a lid 7, in which has been cut out the lighting opening 8, above which there is placed a grate 10 with a number of small holes for supporting the tobacco. In the drawing the lighting 45 opening 8 is shown as being accessible from 50

the side but it can of course be cut out so as to face any other suitable direction.

When the pipe is to be used, the lid 7 is first removed and the combustion shell 2 is then filled with the tobacco to be smoked. 55 This being done the lid is again put on and the pipe lit through the opening 8. The flame is drawn through the holes 9 and lights the tobacco, the smoke being carried away through the openings 3, the cavity 4, the tube 60 5 and to the mouth-piece 6 of the pipe.

What I claim is:—

1. In smoking pipes of the type wherein the combustion proceeds from the bottom upwards, a bowl having an open lower end 65 and being in communication with a smoke conduit, a removable cap-shaped lid at the lower end of the pipe bowl, a grate arranged above and spaced apart from the bottom of said lid to provide a chamber therebetween, 70 and a lighting channel in the lid, said channel extending through the wall of the lid from the outside thereof to the chamber between the said grate and bottom.

2. In smoking pipes of the type wherein the combustion proceeds from the bottom upwards, a bowl having an open lower end, a removable cap-shaped lid at the lower end of the pipe bowl, a grate located within the lid above and spaced apart from the lower 80 part thereof, and an opening for lighting the pipe, said opening being located in the said lid below the grate.

3. A smoking pipe comprising a bowl which is open at the bottom, and the top and lateral parts of which are made integral with the adjacent part of the pipe stem, a tobacco receiving shell within the bowl, said shell being open at the bottom and having an outer flange at its lower edge, a cap removably fitted on the lower end of the bowl, a grate arranged at some distance above the bottom of the cap, the arrangement being such that the grate and the said flange will lie between parts of the bowl and cap, and an opening 95 for lighting the pipe, said opening being located in the wall of the cap below the grate.

4. In smoking pipes of the type wherein the combustion proceeds from the bottom upwards, a bowl having an open lower end, a 100

removable cap-shaped lid at the lower end of the pipe bowl, a grate located within the lid above and spaced apart from the lower part thereof, and an opening for lighting the pipe, said opening being located in the said lid below the grate, the cap-shaped lid being counter-sunk at its upper edge to form a seat for the grate.

5. A smoking pipe comprising a bowl having a closed top and an open bottom, a tobacco receiving shell inserted in said bowl and having an open bottom and an apertured top portion spaced apart from the top of the bowl, a cap removably secured to the open lower end of said bowl, a grate arranged at some distance above the bottom of the cap, said cap having a passage therethrough for lighting said pipe, which passage is located below the grate, the cap being secured to the bowl by an upper flange on the cap fitting around a lower flange on the bowl.

In testimony whereof I affix my signature.

ANDERS HILMER OLSSON.
